GAS SAMPLING SYSTEM

Gerald L. Hassler, Berkeley, Calif., assignor to
 Shell Development Company, San Francisco,
 Calif., a corporation of Delaware

Application December 20, 1938, Serial No. 246,835

3 Claims. (Cl. 23—257)

This invention pertains to the analysis of gaseous mixtures, and relates more particularly to containers for storing gases and to methods for delivering gaseous mixtures to and from said containers without contamination by impurities or dilution by atmospheric air.

This invention is particularly useful in application to methods of underground exploration, whereby indications of the presence of substances, such as oil, in certain formations are derived from the analysis of gases drifting by diffusion upwards to the surface of the ground. It is known that when samples of such gases are collected from a plurality of stations gradually approaching an oil deposit from any direction on the surface of the ground, the amount of gaseous hydrocarbons, and the ratio of ethane and higher hydrocarbons to methane in said soil gases also gradually increases owing to the fact that the higher hydrocarbons diffuse through the soil layers at a slower rate than methane. Since, however, the concentration of the hydrocarbons in the samples obtained is exceedingly small, amounting, for example, to about 3 to 300 parts per million, it is obvious that extremely accurate methods must be used in obtaining, storing and analyzing said soil gases to obtain data of any value from an exploration standpoint.

A suitable method and apparatus for obtaining soil gas samples is described in my application Serial No. 190,473, filed February 14, 1938, and a suitable method and apparatus for analyzing said samples is described in my application Serial No. 237,914, filed October 31, 1938.

The object of the present invention is to provide a suitable storage system for samples of gas obtained underground, said system comprising double-walled containers constructed in such a manner and of such materials as to avoid the contamination of the samples due to leakage, diffusion or adsorption phenomena.

It is also the object of this invention to provide a system for delivering gas samples from their sources to said containers and then to the analytical apparatus without passing said samples through any pumps or other mechanical parts requiring lubrication and therefore likely to contaminate the samples by the exhalation of hydrocarbon particles.

These and other objects of the invention will be understood from the following description taken with reference to the attached drawings wherein:

Fig. 1 is a diagrammatical side-elevation view

in cross-section of a preferred embodiment of this invention;

Fig. 2 is a front elevation view of the same device drawn to a smaller scale;

Fig. 3 is a plan view of the valve plate 6 shown in Figs. 1 and 2;

Fig. 4 is a flow diagram schematically showing the method of filling the device of Fig. 1 with a sample of underground gas;

Fig. 5 is a flow diagram showing the method of delivering a gas sample held in the device of Fig. 1 to an analytical apparatus;

Fig. 6 is a diagrammatical elevation view in cross-section of another preferred embodiment of this invention; and

Fig. 7 is a flow diagram schematically showing the method of filling the device of Fig. 6 with a sample of underground gas.

Fig. 1 shows diagrammatically and in cross-section one preferred embodiment of the invention, which comprises a double-walled, flexible bag, having an outer envelope 3 and a concentric inner envelope 5. This bag is made of material having a very small permeability and no tendencies for adsorption or exhalation of hydrocarbon gases. It has been found that Cellophane is especially suitable for this purpose. Cellophane, which is marketed in the form of tubular rolls, may be conveniently cut into tubular sections of any desired length. Two such tubular sections, inserted into one another, have their upper and lower ends clamped between an inner metallic stem 1, and an outer metallic member 2, which is bent to a near-annular shape around the stem 1, whereby an air-tight fit is insured without the use of any glue, cement or other material capable of contaminating the gaseous contents of the bags by exhalation of impurities.

Both the inner and the outer bags are in communication with the outside by means of a valve structure comprising a metallic plate 6. Openings 7 and 7A are drilled through plate 6, and are of an enlarged diameter 8 on the side facing the bag. The walls of the openings 8 are screw-threaded and adapted to receive plugs 10 and 10A, provided with central passages corresponding to the openings 7 and 7A.

A circular hole is punched in the outside wall 3 of the flexible bag and the edges of the wall around said hole are caught in air-tight manner between the plate 6 and the nut 10, screwed into opening 8 of said plate. A second hole is punched through both walls 3 and 5 of the bag, and the edges of said walls are secured to the plate 6 in the same manner by means of plug 10A.

Plate 6 may be affixed, for example, by means of screw 14, to a panel 15, having passages 16 and 17 communicating between the openings 7 and 7A of the plate, and pipes 20 and 20A, or 21 and 21A, by means of which gaseous mixtures are forced into the double-walled bag or withdrawn therefrom. Pins 9 and 9A are affixed to the panel 15 in register with the openings 7 and 7A. All-metallic flap-valves 12 and 12A, having no rubber parts, and requiring no lubrication (either of which might contaminate the sample due to a possible exhalation of hydrocarbons) are held in a normally closed position within passages 7 and 7A between plugs 10 and 10A and the plate 6. When the plate 6 is clamped to the panel 15 by means of screw 14, the pins 9 and 9A press against the flap-valves 12 and 12A and open said valves.

In operation, the following procedure may be followed in filling the present bag container with gases obtained underground, and in subsequently delivering said gases to an analytical apparatus.

The container is first attached, by means of plate 6 and screw 14, to the panel 15 in such a manner that the inside of the bag 3 is in communication with pipe 20, and the inside of bag 5 with pipe 20A.

Pipes 20 and 20A form part of a soil gas sampling apparatus such as described in my application Serial No. 190,473, filed February 14, 1938, 30 pipe 20 leading to a guard ring space between packers 38 and 39 of a probing borehole, and pipe 20A leading to a space 41 from which it is desired to collect the sample, as shown in Fig. 4.

Pipe 20 is provided with a pump 33, and pipe 35, 20A with a pump 34, which are preferably of the auto-pulse metal-bellows type, which do not require any lubrication, whereby contamination of the sample is avoided.

The intake of pump 33 is connected with the pipe 20A by a pipe 35 provided with a valve 32. A valve 31 opens to the atmosphere between the pump 33 and the bag 3.

With valve 32 closed and valve 31 open, both pumps are started, whereby contaminated air is removed from spaces 40 and 41. Bag 5 expands within the bag 3, which is open to the atmosphere, and forces the air out of said bag 3. After continuing this operation for a desired length of time, valve 31 is closed and valve 32 is opened. 50 Pump 34 is stopped, only pump 33 continuing to operate, whereby the gas from bag 5 is transferred to bag 3, bag 5 becoming entirely evacuated and collapsing within bag 3. Valve 32 is then closed, valve 31 opened, and the pumping 55 proceeds with both pumps operating until both bags are filled to the desired pressure.

The screw 14 is then unscrewed and the plate 6 removed together with the bag from the panel 15, whereby valves 12 and 12A are automatically closed. The sample obtained in this manner may be left in the present container for a considerable length of time, no contaminations by diffusion of atmospheric air through the elastic partitions being possible, since the space within the inner concentric bag 5, containing the sample to be analyzed, is separated from the atmospheric air by the space within the outer concentric bag 3, filled with substantially the same gaseous mixture as bag 5.

70 When it is desired to analyze the gas sample, the gas bag is affixed, by means of the plate 6 and a screw 14A, to the same or a different panel 15, the bags 3 and 5 being respectively in communication with pipes 21 and 21A. As shown in Fig. 75, pipe 21 is connected to a pump 33A, having an

intake open to the atmosphere, while pipe 21A, which is provided with a valve 32A, communicates between the inside of the bag 5 and the analytical apparatus schematically shown at 50. By opening valve 32A and pumping air into the bag 3, the gas sample is forced out of the inner bag into the analytical apparatus. The amount of contamination by diffusion which occurs during this operation due to the presence of atmospheric air in the outer bag 3 is negligible in view of the relatively short duration of said operation.

The containers described above have the advantage of being well suited for operation in the field, being made of resilient material and therefore unbreakable. 15

Should the operating conditions permit, another preferred type of the present containers may likewise be used, wherein only one of the double walls is made of Cellophane, while the other is made of glass. This type of container is 20 preferable for operation under conditions of a very dry atmosphere, which sometimes may result in the cracking and leakage of the double-walled Cellophane bag.

Referring to Fig. 6, a section of tubular Cellophane 5 is inserted within a glass cylinder 3A, approximately 20 inches long and having a diameter of about 2½ inches. The ends are sealed by turning the Cellophane over to the outside to make a tight fit against the fire-polished edges of the glass tube. The space inside the Cellophane is then sealed, at the lower end, by a brass plate 51, fitting in air-tight fashion over the Cellophane and the glass tube, and, at the upper end, by an additional piece of Cellophane 5A and by 35 a piece of dental dam rubber 53, both Cellophane and rubber being held in airtight fashion against the glass by means of wire 52.

The space within the Cellophane bag communicates with the outside by means of a conduit 40 54, fitted through plate 51 and the space between the glass and the Cellophane, which is used for the storage of the sample, communicates with the outside by means of a tube 55. By stretching the dental dam rubber 53, and clamping a suitable 45 stopper such as a rubber ball 56, against the orifice of tube 55 on the inner side of container 3A, the gas sample may be, when desired, securely sealed within the space between the glass tube 3A and the Cellophane bag 5. 50

The tubes 54 and 55 are led into a bushing structure or chamber comprising a rigid metallic or glass tube portion 60 and a rubber tube portion 61, held together in air-tight fashion by means of wire 62. This bushing is closed at either end in air-tight fashion by stoppers 63 and 64, made of suitable materials such as rubber, tubes 54 and 55 passing through stopper 63, a tube or orifice 20, and a tube 20A, respectively, similar to tubes 20 and 20A of Figs. 4 and 5 passing through stopper 64. Tubes 54 and 55 are provided with nipples 65 and 67, whereby either of said tubes can be put in communication with tube 20A. 60

Fig. 7 shows the connections diagram used in filling this embodiment of the present gas container with an underground gas sample by means of the apparatus of my application Serial No. 190,473, filed February 14, 1938.

The tube 20, opening to the guard ring space 40, is connected, by means of a tube 70, with a source of vacuum 71, such, for example, as the pumps shown in Figs. 4 and 5 or as a jar partially filled with a liquid and connected by means of a flexible tube 74 to another jar 73, the degree 75

of vacuum in jar 71 being regulated by raising or lowering the jar 73.

With the pipe 20A in the position shown in Fig. 7, that is, with the tube 20A not engaging either nipple 65 or nipple 67, vacuum is applied to the space within the bushing 60-61, emptying both chambers of the container and drawing from the guard ring space 40 and from the sample space 41 the air contaminated by contact with the atmosphere. The tube 20A is then connected to the nipple 67, whereby vacuum is applied through the space within bushing 60-61 to the guard ring space 40 and to the space between the glass tube 3A and the Cellophane 5, causing said Cellophane to adhere to the glass, whereby the Cellophane bag 5 is expanded, and gas from sample space 41 is drawn thereinto through tube 20A, nipple 67 and pipe 54. The tube 20A is then disconnected from nipple 67 and connected to nipple 65, which can be easily effected by slightly stretching and twisting the elastic part 61 of the bushing. Vacuum is now applied through tubes 70, bushing 60-61, and tube 54, to the space within the Cellophane bag 5, causing said bag to collapse within the glass tube 3A, whereby the gas from the sample space 41 is drawn into the space between the glass and the Cellophane. It will be noted that during the operation of drawing the sample to said space, a higher vacuum is being applied to the guard ring space 40, according to the teachings of my application Serial No. 190,473, filed February 14, 1938. This is due to the fact that the guard ring space 40 is directly in communication with the source of vacuum by means of tubes 70 and 20, while the sample space 41 is indirectly in communication with the source of vacuum by means of tube 20A, nipple 67, tube 54, Cellophane diaphragm 5, tube 55, bushing 60-61 and tube 70, the additional resistance being sufficient to insure the desired pressure differential.

It will also be noted that with the arrangement described above, any leakage resulting from a break or a faulty connection will always be directed from the gas sample into the atmosphere, and not from the atmosphere to the gas sample, whereby any contamination of the sample is avoided.

I claim as my invention:

50 1. In a gas sampling system, two concentric envelopes one wholly within the other, said envelopes being sealed from each other and from the atmosphere, at least the inner envelope being made of flexible material, a conduit in com-

munication with the inside of the inner envelope, a second conduit in communication with the inside of the outer envelope, and means for selectively applying to the other ends of said conduits a gaseous pressure, whereby either envelope 5 may be filled by applying a vacuum to the other envelope, and may be emptied by applying a positive pressure to the other envelope.

2. In a gas sampling system, two concentric flexible gas-impervious envelopes one wholly within the other, said envelopes being sealed from each other and from the atmosphere, a normally closed valve structure in communication with the inside of the inner envelope, a normally closed valve structure in communication with the 10 inside of the outer envelope, two tubular conduits, means for clamping said tubular conduits in register with said valve structures, members rigidly affixed to said clamping means adapted to open said valves when said valves are clamped in 15 register with said conduits, and means for selectively applying to the other ends of said conduits a gaseous pressure, whereby either envelope may be filled by applying a vacuum to the other envelope, and may be emptied by applying a positive 20 pressure to the other envelope.

3. In a gas-sampling system, a rigid gas-tight tubular member, a flexible gas-tight tubular member wholly within said rigid tubular member, sealing means forming a gas-tight bond between the rims of said tubular members at either end thereof, whereby an annular gas-tight space is formed between said tubular members, gas-tight means closing the open ends of said 30 flexible tubular member, whereby a second gas-tight space is formed within said annular gas-tight space, a gas-tight chamber, a gas conduit 35 in communication between said chamber and the annular space between the rigid and the flexible tubular members, a second gas conduit in communication between said chamber and the space within the flexible tubular member, a tube having an outer end immersed in the space from which the sample is collected and an inner end projecting into said chamber, said inner end being adapted for sealing engagement with either of the conduits opening to said chamber, an orifice through the walls of said chamber, and means for selectively filling the space on either 40 end of said flexible envelope with a gaseous sample by connecting said tube to either of said conduits and applying a vacuum to said orifice.

GERALD L. HASSSLER.
